UNITED STATES PATENT OFFICE.

ROBERT T. BROCKMAN, OF TERRE HAUTE, INDIANA, ASSIGNOR TO INTERNATIONAL MONEY MACHINE COMPANY, OF TERRE HAUTE, INDIANA.

MONEY-HANDLING MACHINE.

1,260,310.

Specification of Letters Patent. Patented Mar. 26, 1918.

Application filed January 28, 1915. Serial No. 4,893.

To all whom it may concern:

Be it known that I, ROBERT T. BROCKMAN, a citizen of the United States, residing at Terre Haute, in the county of Vigo and State of Indiana, have invented certain new and useful Improvements in Money-Handling Machines, of which the following is a specification.

This invention comprises certain improvements in money handling machines and especially in machines of the type disclosed in the application of White, Overlin and Bullington, Serial Number 702,164, filed June 7, 1912, which latter machine consists of a key-board section which is virtually a complete adding machine of itself, and a money paying section the operation of which is controlled from the keys of said adding section. Depression of the keys effects operation of certain selector mechanism capable of acting upon the ejectors of the money paying section whereby upon turning a suitable operating handle the money will be discharged from the machine.

There is provided in the above described combined money paying and adding or calculating machine suitable controlling means operable manually, whenever desired, in order to disconnect the money paying mechanism from the main actuator or handle so that the adding or calculating machine is susceptible of operation independently of paying out of money by said money paying mechanism. In the machine of the aforesaid application the selector mechanism controlled by the keys, and which is provided solely for the purpose of coöperation with the ejectors of the money section, continues to be operated notwithstanding the disabling of the connection between the main actuator and the money paying section, said connection being one provided for driving the ejectors.

An especial object of the present invention, therefore, has been to improve the means for disabling the operative connection between the calculating or adding machine and the money paying section so that not only is the disabling device operable to disable the driving means for the ejectors, but an operating connection leading from the main actuator to the selector mechanism which sets said ejectors is likewise, by reason of the particular improvements herein-after described, completely disabled by the

means just referred to, the various parts of the money paying mechanism are practically totally disabled so that certain unnecessary and resultless operation of parts of the money paying machine is avoided affording a saving of wear and tear upon such parts and decreasing furthermore the load on the operating handle or main actuator. In other words, the disabling means above referred to when operated serves to entirely disconnect the ejector actuating movement of the selector mechanism as well as all ejecting action of the ejectors themselves, the adding or calculating machine instrumentalities then being operable independently of the normal operations of the selecting and ejecting devices when the combination machine is being utilized.

The invention also embodies other detail features of improvements which will be described more clearly hereinafter in conjunction with the accompanying drawings, in which—

Figure 1 is a partial front elevation of a machine embodying the invention, the adding mechanism illustrated partly in section, and the operative connection between the actuator and the selector mechanism being shown.

Fig. 2 is a sectionalized right side elevation of the coin paying section, a section being taken just slightly to the right of the single and double pay \$20.00 coin magazine.

Figs. 3 and 4 show a plan view and right side elevation of the mechanism for disengaging the rock shaft which operates the selector mechanism, and the means to disable the ejector mechanism.

Fig. 5 is a sectional view through the calculating machine section of the combined machine.

General construction of the machine.

The calculating or adding section of the machine is designated A and the money paying section B. The calculating section embodies suitable amount keys C and a disabling key D. It is not believed necessary to describe the details of the mechanisms of either of the sections A and B, these being practically the same in broad principle of action and coöperation of parts as any Burroughs type adding machine, and also the corresponding mechanisms of the application previously identified, and this invention not

involving the details of the adding machine whatever. In Fig. 5 the main parts of the adding or calculating mechanism are illustrated, the accumulator being located 5 at the front of the machine and including the adding wheels 84 and the adding racks 82, the movement of the latter being controlled by engagement of a projection 80' on each rack with index stops 90, the latter operable by the various keys C of the keyboard. The lower ends of the racks 82 are connected with levers 75 at the front ends of the latter, said levers being connected at their rear ends with type bars 95 forming 10 a part of suitable listing mechanism. Suitable springs 76 connect with arms 75' of the levers 75 to actuate the latter when released incident to operation of the main handle F of the machine. It may be noted, 15 however, that the money paying section B is virtually a complete and separate functioning mechanism, to work jointly with the calculating mechanism, or remain inactive with regard to the latter, and comprises the 20 money holders or coin receptacles E at the base portions of which operate the ejectors or actuating members for coins, or the like, designated 1307, the majority of the ejectors being adapted to eject a single coin from the 25 associated coin holder E, but certain ejectors being susceptible of adjustment in operation, to discharge one or two coins, this being desirable in order to make up certain amounts where two pennies, two nickels or 30 two coins of other denominations are preferably ejected. The ejectors 1307 are provided at their rear ends with lateral projections 1307' (see Fig. 2). Normally these projections 1307' are not engaged with ejectors 35 for arms 545 one of which is provided for each ejector and mounted on the ejector shaft 615. By the provision of selector mechanism including the selector bars a having projections a' any one or more of 40 the ejectors 1307 may be moved laterally at its rear end to interlock the projection 1307' with the adjacent arm 545. This interlocking is effected by a longitudinal movement imparted to the selector bars a, at 45 the commencement of the forward pull on the handle F which is the main actuator, if the selector bars a are previously set in a position to be engaged by a selector bail 520 (see Fig. 1). The amount keys C of 50 the keyboard A are adapted to engage projections a' of one or more of the selector bars a when the keys C are depressed. Such of the bars a as may be depressed by the action of the keys C will have hooks formed 55 at one end thereof engaged with the bail 520 so that when the bail 520 rocks rearward as seen in Fig. 1, longitudinal movement will be imparted to the bars a that have been thrown into co-operation with the bail. The 60 longitudinal movement of the actuated bars

a is transmitted to the rear ends of the ejectors 1307 associated with such bars, through the projections 1307' and these ejectors are thus interlocked with bifurcations at the lower ends of the coacting arms 545 on the 70 ejector shaft 615. The means to actuate the bail 520 are shown clearly in Figs. 3 and 4 and comprise an arc-shaped cam fixed to the main shaft 625 carrying the handle F, said cam co-operating with a roller 691 of the lever 523 carried by the rock shaft 674. The lever 523 is connected by a link 522 with an arm 521 projecting from the shaft 520' to which the bail 520 is fixedly attached. It will thus be seen that so long as the connection 80. 75 85 90 95 100 105 110 115 120 125 130

522 is at normal as shown in Fig. 4, each time the handle F is pulled forward the cam 502 will rock the bail 520 and actuate the selector bars a engaged with said bail by means of the keys C.

The ejector shaft 615 is likewise operable from the main shaft 625 through the provision of the forked lever 515 coacting with an arm 625' tiltable by the movement of the shaft 625. The lever 515 is carried by a 90 stub shaft 515' mounted in the left side frame of the adding section A, and the shaft 515' carries the arm 515" provided with a stud 515* at its upper end co-operative with the hook 542. The hook 542 is carried by 95 an arm 615' on the ejector shaft 615 and a spring 615" holds the hook 542 yieldingly engaged with the stud 515*.

Disabling of paying mechanism.

It being borne in mind that the instrumentalities just described provide connections of the selector bail 520 and the ejector shaft 615 with the main shaft 625, and that operation of the shaft 625 will correspondingly simultaneously actuate the bail 520 and shaft 615 when the parts are at normal, the means to disable the connections just mentioned will now be set forth. The disabling key D previously referred to has a projection 282 at its lower end engageable with the arm b on the second stub shaft c (see Figs. 3 and 4) the latter carrying a long arm d disposed above the hook 542 and adapted to force said hook whereby to 110 disengage the parts 542 and 515* when the key D is depressed and held depressed by the notch D' near its upper portion engaging with the top of the keyboard. Obviously when the parts 542 and 515* are disengaged, movement of the main actuating shaft 625 is not transmitted to the ejector shaft 615 so that the latter will remain idle. Thus far the instrumentalities set forth are substantially the same as presented in the 125 previous application referred to. However, in addition to the disabling of the ejector shaft 615 the key D serves as a means to disable the connection between the shaft 625 and the selector actuating bail 520. For this 130

purpose a shaft 229 mounted in the adding section A is provided with an arm 163 and an arm 161, the latter being spring-retracted by the spring 161'. At its lower end the 5 arm 163 has a projection engaging the lever 949 intermediately pivoted on the axis 1033, said lever having a link connection 950 with the link 522. Thus it is that depression of the key D causes a rocking of a lever 161* 10 on the shaft 229, through engagement of the projection 282 with the lower curved end of said lever 161*. The arm 161 is a part of the lever 161* and rocking of the shaft 229 by the member 161* correspondingly rocks 15 the lever 949, exerts a pull on the link 950 and carries the link 522 toward the rear whereby to disengage a stud 675 on the lower end of said link 522, from the arm 521. In this manner, therefore, the selector bail 20 520 may be disabled. The disabling of the selector means through the above operation is advantageous for the reason that said means is only used as a part of the money paying section of the machine and in the 25 machine of the previously mentioned application, of which this is a continuation in part, the disabling of the paying section B was not complete, as is the case in the present construction, owing to the actuation of 30 the selector bars and the ejectors connected thereto, the latter, of course, not performing any ejecting movement.

It is evident that so far as the section B of my machine is concerned this section is, 35 in a broader sense, a predetermining mechanism which comprises actuators in the form of the ejectors 1307 whereby money transactions are adapted to be effected. These money transactions may take the form, of 40 course, of money ejection or money predetermining by way of registration, it being known in the art that registers are susceptible of being operated by actuators such as the ejectors 1309 whereby amounts of trans- 45 actions of money set up on the adding machine may be divided into units of various denominations which go to make up each transaction or amount accumulated.

Having thus described the invention, what 50 is claimed as new is:

1. In combination, a calculating machine embodying manipulative controlling instrumentalities, a money paying mechanism associated with said machine and comprising 55 money paying devices controlled by said controlling instrumentalities of the calculating machine, said mechanism including means to operate the paying devices and selector mechanism to control said paying devices preliminary to operation, and a controlling device operable for disabling the operating means for the paying devices and for disabling said selector mechanism whereby the calculating machine is susceptible of 60 operation alone.

2. In combination, a calculating machine embodying manipulative controlling instrumentalities, a money paying mechanism associated with said machine and comprising money paying devices controlled by said controlling instrumentalities of the calculating machine, said mechanism including means to operate the paying devices and selector mechanism to control said paying devices preliminary to operation, a manipulative member, and means operable by said member to simultaneously disable the operating means for the paying devices and the selector mechanism controlling the same devices. 70 75 80

3. In combination, a calculating machine complete in itself and comprising manipulative controlling devices and a prime mover, money paying mechanism associated with said machine and comprising paying devices, operating means for the paying devices connected with the prime mover aforesaid, selector mechanism intermediate the controlling instrumentalities and the paying devices, and means to simultaneously disable 90 the selector mechanism and disconnect the operating means for the paying devices from the prime mover. 85 90

4. In combination, a calculating machine comprising manipulative controlling members and a prime mover, a money paying mechanism including paying devices, selector mechanism controllable by said controlling members and co-operative with the paying devices, an operating connection between the prime mover and the selector mechanism to actuate the parts of the latter under the control of the manipulative members, operating means for the paying devices, a connection between said operating means and the prime mover, and means to simultaneously disconnect said operating means for the paying devices and the operative connection for the selector mechanism from the prime mover. 95 100 105 110

5. In a machine of the class described, the combination of money paying devices, keyboard mechanism including amount keys, an accumulator controlled by said amount keys, a main actuator for the accumulator, selector mechanism for the paying devices, an operative connection between the main actuator and said selector mechanism, operating means for the paying devices, an operative connection between the operating means aforesaid and the main actuator, a disabling key, and means intermediate said key and the operative connections between the main actuator and the selector mechanism whereby to render said operative connections inactive. 115 120 125

6. In a machine of the class described, the combination of money paying mechanism including paying devices, selector mechanism therefor comprising selector bars, a 130

- selector bail coöperative with said selector bars, calculating mechanism including manipulative controlling keys capable of moving the selector bars into operative relation 5 in respect to the selector bail, a main actuator, an operative connection between the main actuator and the selector bail, an operative connection between the main actuator and the operating means for the paying devices, a disabling key, and means controlled from said key to simultaneously disconnect the main actuator from the selector bail and render inoperative the connection between the main actuator and the operating 10 means for the paying devices.
7. The combination with a calculating machine including operating instrumentalities therefor, of special functioning mechanism comprising selecting and actuating means controlled from said operating instrumentalities of the calculating machine, and mechanism to disable the controlling action of said operating instrumentalities in relation to both the selecting and actuating 15 means of said special mechanism.
8. The combination with a calculating machine including operating instrumentalities therefor, of special functioning mechanism for action conjointly with the calculating machine comprising selecting and actuating means movable by said operating instrumentalities, and means to interfere with the movement of the selecting and actuating means by the calculating machine instrumentalities whereby discontinuance of the combined operation of the calculating and selecting means may be effected.
9. The combination with a calculating machine including operating instrumentalities 40 therefor, of money handling mechanism comprising ejecting means and selecting devices to actuate the same, moving connections intermediate the operating instrumentalities and said ejecting means and selecting devices, and means to disable said moving devices, and means to disable said moving connections whereby combined paying out and selecting functioning of the said parts may be discontinued.
10. The combination with a calculating machine including predetermining keys, operating instrumentalities, of conjointly operable mechanism comprising selecting means controlled by said keys and ejecting means controlled from said keys and operating instrumentalities of the calculating machine, and mechanism to interfere with the controlling action of said operating instrumentalities in relation to both the selecting and ejecting means, so that the said machine and mechanism may be disabled as regards 55 conjoint operation, the calculating machine and the conjointly operable mechanism embodying frame structures and connections between said frame structures.
- 60 65 11. The combination with a calculating

machine including operating instrumentalities therefor, of conjointly operable mechanism comprising actuating members and selecting devices to actuate the same, moving connections intermediate the operating instrumentalities and said actuating members and selecting devices, the calculating machine embodying a frame structure and the actuating and selecting means being supported by a frame structure, and means to 70 disable said moving connections without disturbing the relation of the frame structures aforesaid, whereby combined calculating functioning and operation of the actuating and selecting parts may be discontinued. 75 80

12. The combination, with a calculating machine including manipulative predetermining devices, and operating instrumentalities, of special functioning mechanism adapted to operate conjointly with the calculating machine and including selecting devices controlled from said manipulative predetermining devices, connections whereby the operating instrumentalities of the calculating machine may actuate said selecting devices, and means to disable the special functioning mechanism in relation to the calculating machine including mechanism for rendering inoperative the connections between the operating instrumentalities and 95 the selecting devices so that the operating instrumentalities may be relieved of the load incident to actuating the selecting devices when the special functioning mechanism is disabled. 100

13. The combination, with a calculating machine comprising manipulative predetermining devices, and operating instrumentalities, of a special functioning mechanism adapted to be operated conjointly with the calculating machine and including selecting devices and actuating members adapted to be selected for operation by said selecting devices, said selecting devices and actuating members being controlled by the said predetermining devices of the calculating machine, and means to disable the special functioning mechanism aforesaid to permit operation of the calculating machine while the special functioning mechanism is inactive, 105 said last mentioned means including connections operable in such a manner as to relieve the operating instrumentalities of the calculating machine of the load incident to the actuation of the selecting devices and 110 actuating members.

14. In combination, a money predetermining mechanism comprising actuators adapted to effect money transactions, operating means for said actuators, and selector mechanism adapted to coact for purposes of setting the operating means with respect to the actuators, an accounting machine including manipulative controlling instrumentalities, arranged to control the selector mechanism 115 120 125 130.

aforsaid, and a prime mover for the accounting machine operatively connected with the selector mechanism for actuating the latter, and means whereby to disable the 5 last named operative connection and thereby discontinue the operation of the selector mechanism by the prime mover, and thus rendering the predetermining mechanism

inactive relatively to the accounting machine.
